UNITED STATES PATENT OFFICE.

EARL G. FIDLER, OF GARRETT, PENNSYLVANIA, ASSIGNOR OF ONE-HALF TO LEE W. POLLARD, OF GARRETT, PENNSYLVANIA.

BALLAST-PLOWING DEVICE.

Application filed January 14, 1924. Serial No. 686,230.

To all whom it may concern:

Be it known that I, EARL G. FIDLER, a citizen of the United States, residing at Garrett, in the county of Somerset and State 5 of Pennsylvania, have invented certain new and useful Improvements in Ballast-Plowing Devices, of which the following is a specification, reference being had to the accompanying drawings.

10 This invention relates to a ballast plowing device and it is an object of the invention to provide a novel and improved device of this general character adapted to be applied to rolling stock and which 15 operates effectively to spread and distribute ballast.

Another object of the invention is to provide a novel and improved device of this general character which operates to effect 20 a material saving of labor in what is commonly known by trackmen as "ballast dressing" and which works both between rails of a trackway and the regulation distance outside of the trackway.

25 Furthermore it is an object of the invention to provide a novel and improved device of this general character which is adapted to travel along the rails of the trackway together with lubricating means to facilitate such travel.

An additional object of the invention is to provide a novel and improved device of this general character comprising a member adapted to be disposed upon the rails 35 of a trackway and having plowing elements carried thereby adapted to extend between the rails, said elements being each secured to the member in a manner whereby such elements may be separated from the member independently of the other members upon abnormal resistance or impact.

The invention also has for an object to provide a device of this general character comprising a member adapted to travel over 45 the rails of a trackway together with a second member adapted to be mounted upon the first named member to prevent the ballast from passing over the top of the first named member during a working operation.

50 The invention consists in the details of construction and in the combination and arrangement of the several parts of my improved ballast plowing device whereby certain important advantages are attained and

the device rendered simpler, less expensive 55 and otherwise more convenient and advantageous for use, as will be hereinafter more fully set forth.

The novel features of my invention will hereinafter be definitely claimed. 60

In order that my invention may be the better understood, I will now proceed to describe the same with reference to the accompanying drawings, wherein:—

Figure 1 is a view in perspective of a 65 ballast plowing device constructed in accordance with an embodiment of my invention, the guard or shield being omitted;

Figure 2 is a view in perspective of the guard or shield as herein disclosed; 70

Figure 3 is a view partly in section and partly in elevation illustrating my improved device as herein disclosed in working position, said section being adjacent to an end of the device; 75

Figure 4 is a view partly in section and partly in elevation of the device as herein disclosed, the line of section being substantially central to the device;

Figure 5 is a fragmentary view partly 80 in section and partly in elevation of the device as herein disclosed.

As disclosed in the accompanying drawings, 1 denotes an elongated member or beam of desired dimensions and which is 85 provided in its under surface at desired points inwardly of its opposite ends with the recesses 2 adapted to fit upon the heads of the rails R whereby the member 1 may be supported by such rails and readily move 90 or slide thereover. The lower portion 3 of the member 1 intermediate the recesses 2 is permitted by the recesses 2 to drop a desired distance below the top of the rails R. 95

Disposed through the member 1 and in communication with the recesses 2 are the vertically disposed openings or holes 4 each having therein a filler 5 of cotton or other absorbent material which is adapted to be saturated with a suitable lubricant. As the 100 member 1 travels over the rails R the lubricant will work down and pass out upon the top of the rails R and to an extent to maintain the walls of the recesses 2 sufficiently lubricated to cause the member 1 105 to travel over the rails with greater facility and ease.

Underlying the bottom face of the inter-

mediate portion 3 of the member 1 are the blocks 6, herein disclosed as three in number. The blocks 6 are in close contact with such under face and are held thereto by 5 the boat spikes 7. These spikes 7 also hold to the under face of each of the blocks 6 a wear plate 8 of sheet iron, said plates having their forward margins provided with an upstanding flange 9 overlying the forward face of the associated block 6, said flange 9 serving to prevent the plate from wearing loose from the block.

The forward face of the member 1 preferably inwardly of but in close proximity to 15 the recesses 2 is provided with the notches 10 in which are secured extremities of the chains 11 and 11^a, one of said chains, as 11^a, being of a length greater than the other chain 11. These chains provide means 20 whereby the member 1 may be operatively engaged with the rolling stock such as a dumping car used in the initial distribution of the ballast. These chains 11 and 11^a are adapted to be suitably positioned over 25 any desired part of the rolling stock or car such as break rig hangings or frames or, if used ahead of the car, may be coupled to the draw head. The longer chain 11^a, in effecting a connection with the rolling 30 stock or car, is threaded through a ring 12 carried by the outer or free end of the chain 11, the outer portion of the chain 11^a being returned with the hook 14 carried thereby suitably engaged with a link comprised in such chain 11^a. By this means the 35 beam 1 may be applied to or removed from working position with respect to the rolling stock or car in a relatively short period of time and without requiring any particular 40 skill.

The upper rear marginal portion of the member 1 directly above the recesses 2, are provided with the notches 15, the base portions of which being disposed on an upward 45 and inward incline and overlying such base portions and suitably held thereto are the wear plates 17. These wear plates serve to prevent the wheels of the rolling stock or car having direct contact with the member 1 cutting through said member.

In practice, the member 1 is preferably positioned and supported in front of the rear truck of a rolling stock or car and rearwardly of the bottom dumping doors of such 55 stock or car and with the chains 11 and 11^a so adjusted or tightened so that under normal conditions the member 1 will have contact with but slide along on the rails R but should the stock or car be lifted by an obstruction on the trackway or from other causes, the member 1 will also lift with the stock or car whereby liability is substantially avoided of the stock or car being derailed by the member 1.

60 With my improved device in position the

stock or car as the ballast is dumped, is caused to move at a comparatively low speed in the direction the ballast is to be distributed or spread and as the member 1 rides or slides along on the rails R the blocks 6 serve as 70 plowing elements to plow out the ballast between the rails during the time the ballast is being unloaded from the car or if preferred can be employed to the same advantage after the ballast has first been dumped 75 or unloaded upon the trackway.

The end portions of the member 1 outwardly of the recesses 2 serve to effectively distribute or spread the ballast outside of the 80 rails.

If, during a working operation a large stone should be dropped with the ballast upon the trackway, the resistance offered thereby can only result in the tearing or stripping off of one of the blocks 6 and thereby avoid derailment of the stock or car.

The opposite ends of the member 1 are provided with the pockets 18 intersected by a bolt or rod 19 disposed transversely of the member 1, said bolts or rods 19 providing 90 hand holes or grasps to facilitate the handling of the member 1. These bolts or rods 19 also provide anchoring means for a second member 20 adapted to be disposed upon the member 1. The member 20 is of a length 95 substantially equal to the length of the member 1 and when mounted upon said member 1 serves as a guard or shield to prevent the ballast from passing over the top of the member 1 during a working operation whereby the efficiency of the device is materially increased.

Each end portion of the member 20 is provided with a pair of outstanding plates 21 provided with aligned slots 22 disposed in 100 a direction lengthwise of the member 20. Slidably engaged within the slots 22 is a bolt or pin 23 to which is pivotally engaged, between the plates 21 an end portion of the shank or tang 24 of a hook 25. The hook 25 is adapted to be engaged with a bolt or rod 19 whereby the member 20 is effectively maintained in applied position.

To prevent accidental displacement or disengagement of a hook 25 with a bolt or rod 19, the associated shank or tang 24 has 115 slidably mounted thereon a keeper 26.

The slots 22 hereinbefore referred to allow the bolts or pins 23 to move backward in case the device is dropped off a car on some hard surface and thereby prevents bending of the hooks 25 or the shanks or tangs 24.

The outer blocks 6 may be positioned with respect to the recesses 2 as best complies with the requirements of practice, preferably near enough to the rails to clear the track bolts so that no ballast will be left which will have to be removed by hand.

120 It is also to be understood that the device can be employed on any kind of a car and 125

not necessarily a dumping car so that with the use of the device no extra equipment is necessary.

In practice, the plowing device operates effectively to plow the ballast out between the rails down to about level with the ties embedded in the roadbed and to distribute the ballast outside of the rails in about the proper amount so as to require but little 10 hand work or labor.

From the foregoing description it is thought to be obvious that a ballast plowing device constructed in accordance with my invention is particularly well adapted for 15 use by reason of the convenience and facility with which it may be assembled and operated, and it will also be obvious that my invention is susceptible to some change and modification without departing from the principles 20 and spirit thereof and for this reason I do not wish to be understood as limiting myself to the precise arrangement and formation of the several parts herein shown in carrying out my invention in practice except as hereinafter claimed.

I claim:—

1. A device of the character described comprising a member adapted to travel upon the rails of a trackway, attaching means 30 associated therewith, and plow elements secured to the under face of the member.

2. A device of the character described comprising a member adapted to travel upon the rails of a trackway, attaching means associated therewith, plow elements secured to the under face of the member, each of said elements constituting a block, and means for securing each of the blocks to the member.

3. A device of the character described comprising a member adapted to travel upon the rails of a trackway, attaching means associated therewith, plow elements secured to the under face of the member, each of said elements constituting a block, and a 45 wear plate underlying each of the blocks.

4. A device of the character described comprising a member adapted to travel upon the rails of a trackway, attaching means associated therewith, plow elements secured to the under face of the member, each of said elements constituting a block, and bolts securing each of the blocks to the member.

5. A device of the class described comprising, in combination, a member adapted 55 to travel along the rails of a trackway, supporting means therefor, a second member positioned upon the first named member and extending lengthwise thereof, and means carried by the end portions of the first named member and engaging the end portions of the second named member for holding the second member in applied position.

6. A device of the class described comprising, in combination, a member adapted 65 to travel along the rails of a trackway, sup-

porting means therefor, a second member positioned upon the first named member and extending lengthwise thereof, hand grasps carried by the opposite end portions of the first named member, and anchoring elements 70 carried by the second member and engageable with the hand grasps to maintain the second member in applied position.

7. A device of the character described comprising, in combination, a member 75 adapted to rest and travel upon the rails of a trackway, a second member positioned thereon, hook members slidably engaged with the opposite end portions of the first named member, and elements carried by the first named member with which the hook members engage to maintain the second named member in applied position.

8. A device of the character described comprising a member adapted to travel upon 80 the rails of a trackway, said member in its under surface being provided with recesses to fit upon the heads of the rails, attaching means associated therewith and secured to the member inwardly of but in close proximity to the recesses, and plow elements 85 secured to the under face of the member.

9. A device of the character described comprising a member adapted to travel upon 90 the rails of a trackway, flexible attaching means associated therewith, and plow elements secured to the under face of the member.

10. A device of the character described comprising a member adapted to travel upon 100 the rails of a trackway, said member in its under surface being provided with recesses to fit upon the heads of the rails, attaching means associated therewith, plow elements 105 secured to the under face of the member, and wear plates secured to the upper rear marginal portions of the member above the recesses.

11. A device of the class described comprising a member adapted to travel along 110 the rails of a trackway, supporting means therefor, a second member positioned upon the first named member and extending lengthwise thereof, each end portion of the member being provided with a pair of outstanding plates, said plates being provided with aligned slots, pins slidably engaged within the slots, a hook member pivotally engaged with the pin, and means carried by the first named member with which the hook member engages to hold the second named member in applied position upon the first named member.

12. A device of the class described comprising a member adapted to travel along the 115 rails of a trackway, supporting means therefor, a second member positioned upon the first named member and extending lengthwise thereof, each end portion of the member being provided with a pair of outstanding 120 plates, said plates being provided with aligned slots, pins slidably engaged within the slots, a hook member pivotally engaged with the pin, and means carried by the first named member with which the hook member engages to hold the second named member in applied position upon the first named member.

plates, said plates being provided with aligned slots, pins slidably engaged with the slots, a hook member pivotally engaged with the pin, said hook member being mounted upon the pin between the plates, and means carried by the first named member with which the hook member engages to hold the second named member in applied position upon the first named member.

13. A device of the character described comprising a member adapted to travel upon the rails of a trackway, attaching means associated therewith, and plow elements depending from the under face of the member, adjacent elements being spaced.

In testimony whereof I hereunto affix my signature.

EARL G. FIDLER.
